H. W. GOFF

SWITCHING MECHANISM

Filed June 27, 1922

Fig. 1.

UNITED STATES PATENT OFFICE.

HAROLD W. GOFF, OF NEW YORK, N. Y., ASSIGNOR TO WESTERN ELECTRIC COMPANY,
INCORPORATED, OF NEW YORK, N. Y., A CORPORATION OF NEW YORK.

SWITCHING MECHANISM.

Application filed June 27, 1922. Serial No. 571,191.

To all whom it may concern:

Be it known that I, HAROLD W. GOFF, a citizen of the United States, residing at New York, in the county of New York,

5 State of New York, have invented certain new and useful Improvements in Switching Mechanism, of which the following is a full, clear, concise, and exact description.

This invention relates to improvements 10 in switching mechanisms and has particular reference to a switch structure employed in automatic telephone exchange systems.

In the type of switch apparatus generally known as coordinate switches, it has heretofore been customary to provide a single insulated supporting member on which a plurality of sets of active contacts have been collectively mounted. Such an arrangement has necessitated the removal of all of the 20 sets of contacts together with the supporting member therefor when one or more of the sets were to be replaced or repaired.

An object of the present invention is to divide a plurality of sets of contacts into 25 groups, each of which includes a number of said sets combined to form a unit which may be removed from the switch structure without disturbing other units.

In accordance with this object, each unit 30 has a separate supporting member and an operating member which is connected to another operating member common to all the operating members of the individual units of the group.

35 Another object is to provide a switch structure of simple and economical design which will be efficient and reliable in operation.

The above and other objects will appear 40 more clearly from the following detailed description of the switch, when taken in connection with the accompanying drawing, which illustrates a preferred embodiment of the inventive idea.

45 In the drawing, Fig. 1 is a fragmentary vertical longitudinal section of the switch structure; Fig. 2 is a perspective view showing two cooperating sets of active contacts and the operating parts therefor; Fig. 3 is 50 a fragmentary rear elevation illustrating the manner in which the insulated contact supporting members are mounted on the switch frame and held in position thereon.

55 Referring more particularly to the drawing, the switch frame is shown as including

a plurality of horizontally disposed supporting bars 1 which extend transversely across the rear of the frame. Each of these bars is utilized to support a number of vertically disposed and superimposed insulated supporting members 2, adjacent ends of which are recessed as indicated at 3 to receive a longitudinal edge of one of the bars 1. In order to maintain the supporting members 2 in position on the switch frame, a pivot, 60 such as the screw 4, is carried by the bar 1 and disposed at a point between adjacent ends of four of the supporting members 2. Rotatably mounted on the pivot 4 is a substantially circular latching plate 5 which, 65 when in operative position, engages adjacent ends of the supporting members 2 and thus maintains the same in position on the switch frame. Latching plate 5 is provided with a notch 6 in its periphery so that if it is desired to remove any one of the supporting members 2, the latch 5 may be rotated until the notch 6 therein assumes a 70 position where no part of the latch will be engaged with the supporting member which is to be removed. At the same time the other three supporting members engaged by the latch 5 will be maintained in proper position thereby.

75 Each of the supporting members 2 carries a plurality of sets of flexible line contacts 7 extending forwardly therefrom, the contacts of each set being disposed in a horizontal plane. The sets of line contacts 7, supported by each of the members 2, combine 80 to provide a unit and are controlled through the intermediary of an operating member 8 individual to the sets forming said unit. Each member 8 is in the form of a bar 85 which extends longitudinally with respect to the associated supporting member 2, and which is provided at each end with a lateral extension 9 having a slot 10 therein for receiving a pin 11 carried by the line bar 12, which is common to all of the operating 90 bars 8 arranged in the same vertical plane. By thus constructing the bars 8 it is obvious that the same may be readily disconnected from operative relation with the line bar 12 by moving said bars 8 rearwardly until the 95 pins 11 are disengaged from the slots 10.

100 Each set of line contacts 7 is embedded in an insulated block 13 disposed intermediate the ends of the set and normally engaging a stop 14, which limits upward movement 105

of the set of contacts when the same are restored to normal after the connection established thereby is released. Each set of contacts is further provided with a latching member 15, preferably made of a single length of wire having one end secured to an operating member 8 and its other end bent to form a substantially rectangular frame 16, the upper side of which extends 10 through and is loosely mounted in the block 13, whereby the latching member has a pivoted movement therein. The lower side of the frame 16 is further bent to provide a shoulder or flange 17 which, when the latching member 15 is operated, is moved to a position in the path of an associated link bar 18, which is pivotally mounted at its forward edge in a portion of the switch frame as indicated at 19. A grid element is 20 carried by each of the link bars 18 and comprises an insulated strip 20 secured to said bar and having series of transverse slots 21 formed in the upper and lower edges thereof and arranged in staggered relation as indicated in Fig. 2. A plurality of conductors 22 are engaged in the slots 21 and helically wound about the insulated strip 20 to form a set of active link contacts which are moved relative to the sets of line 30 contacts by the rotation of link bar 18 controlled by a magnet 23 having its armature 24 forming a part of said link bar. The construction and operation of the grid element is substantially the same as that disclosed in my copending application, Serial 35 No. 550,617, filed April 8, 1922.

The line bar 12 is controlled by magnet 25, the armature 26 of which is designed to engage a pin 27 carried by the bar 12 adjacent its lower end so that when the magnet 25 is energized the bar 12 is moved downwardly and carries therewith the operating members 8. The latching members 15 of the sets of contacts forming the various units controlled by the line bar 12 are moved about their pivots in the blocks 13 so that the flanges 17 will be positioned in the path of movement of associated link bars 18.

In the operation of the switch one of said link bars is thereupon operated by the energization of its magnet 23 and moves the associated set of link contacts relative to the adjacent set of line contacts 7. At the same time the rear longitudinal edge of the link bar 18 is engaged with the adjacent flange 17 and exerts a pressure upon the latching member 15 and block 13, which causes the associated set of line contacts 7 to be moved downwardly toward the link contacts 22 until said contacts are engaged. A slight additional movement may be imparted to the link bar 18 so as to flex the set of line contacts 7 to maintain the same in close engagement with the link contacts 22 while

the connection therebetween exists. After a connection is established the line bar 12, together with the operating members 8, are restored to their normal positions by the release of magnet 25 and thus all of the 70 latching members 15, which have been actuated by the line bar 12, will be restored to normal, with the exception of the latching member which has been engaged by the operated link bar 18. While the connection is established between the operated sets of contacts 7 and 22, the line bar 12 may again be actuated to initiate the establishment of a coexisting connection through the medium of any one of the other link bars. When a 80 connection is released the magnet 23 of the operated link bar 18 is deenergized, thus permitting said bar to restore to normal when it becomes disengaged from the flange 17 of the latching member 15, and thus 85 allows said latching member, together with the block 13 and set of contacts 7, to restore to normal.

From the foregoing description, when taken in connection with the accompanying drawing, it will be apparent that should it be desired to repair or replace one of the units comprising a plurality of sets of contacts 7, this may be done by simply disengaging the latch 5 from the supporting member 2, which carries said plurality of sets of contacts after which the entire unit may be removed from the switch frame by disengaging the operating member 8 of the unit from the line bar 12. In this manner the unit may be removed without disturbing other units forming a part of the switch structure.

The type of switch in which this invention may be adapted is disclosed in Patent 105 No. 1,515,735, issued November 18, 1924, to Charles L. Goodrum et al.

What is claimed is:

1. In a switching mechanism, a plurality of sets of active contacts arranged in groups each of which forms a unit, a common operating member for said groups, an operating member for each of said groups controlled by said common operating member, means for removably supporting each group in operative relation to said common operating member, a plurality of sets of passive conductors arranged in parallel rows coordinately disposed to said sets of active contacts each of said sets of passive conductors being adjacent to one of said sets of active contacts, a plurality of operating link bars corresponding in number to the said plurality of passive conductor sets, and means operable under the conjoint operation of said common operating member and one of said link bars to effect a connection between a set of active contacts and its adjacent set of passive conductors.

2. In a switching mechanism, a plurality

of sets of active contacts arranged in groups each of which forms a unit, a common operating member for said groups, an operating member for each of said groups, a plurality 5 of sets of passive conductors arranged in parallel rows coordinately disposed to said sets of active contacts, a plurality of operating link bars for said sets of passive conductors, means operable under the conjoint 10 operation of the common operating member and one of the operating link bars to move an active contact set and a set of passive conductors into engagement, the connection being effected through the medium of the unit 15 operating member which is removably connected to and controlled by said common operating member.

3. In a switch structure, a plurality of sets of active contacts arranged in groups 20 each of which forms a unit, a plurality of supporting members one for each of said groups of contacts arranged in vertical rows and a clamping device for securing adjacent supporting members to said structure 25 and arranged to permit the removal of one supporting member without disturbing the other supporting member.

4. In a switch structure, a plurality of sets of active contacts arranged in groups 30 each of which forms a unit, a plurality of supporting members arranged in vertical and horizontal rows each of said members supporting a group of active contact sets, a single clamping device for securing the 35 adjacent members in a horizontal row with also the adjacent members in a vertical row in said structure and arranged to permit the

removal of one member without disturbing any of the other members.

5. The combination in a coordinate switch 40 structure of a frame, a plurality of molded strips of contacts disposed coaxially on said frame, and a notched disc for locking said strips in position thereon and for permitting the unlocking of said strips individually. 45

6. The combination in a coordinate switch structure of a frame, a pair of parallelly disposed contact strips thereon, another pair of parallelly arranged contact strips coaxially disposed relative to the first mentioned pair, a rotatable locking disc therefor, and an adjustable pivot for securing said disc against rotating thereon. 50

7. The combination in a coordinate switch structure of a plurality of pairs of parallel and coaxially arranged strips of contacts, a frame therefor, a notched bar arranged across said frame for locking said strips in an adjusted position thereon, and means rotatable on an adjustable pivot for securing said strips in position in the notches of said bar, and for releasing said strips individually. 55

8. The combination in a coordinate switch 60 structure of a frame, a plurality of parallel contact strips disposed at intervals on said frame, and a disc for locking said strips on said frame collectively and for unlocking the same individually. 65

In witness whereof I hereunto subscribe my name this 26th day of June, A. D., 1922. 70

HAROLD W. GOFF.
